(57) **CLAIM**

The ornamental design for a multi-purpose hand-operated office utensil, as shown and described.

DESCRIPTION

FIG. 1 is a top perspective view of a multi-purpose hand-operated office utensil showing my new design; FIG. 2 is a bottom perspective view of FIG. 1; FIG. 3 is a left side elevational view of FIG. 1; FIG. 4 is a right side elevational view of FIG. 1; FIG. 5 is a top plan view of FIG. 1; FIG. 6 is a bottom plan view of FIG. 1; FIG. 7 is a rear elevational view of FIG. 1; FIG. 8 is a front elevational view of FIG. 1. FIG. 9 is a second top perspective view of my new design of FIG. 1; FIG. 10 is a bottom perspective view of FIG. 9; FIG. 11 is a left side elevational view of FIG. 9; FIG. 12 is a right side elevational view of FIG. 9; FIG. 13 is a top plan view of FIG. 9; FIG. 14 is a bottom plan view of FIG. 9; FIG. 15 is a rear elevational view of FIG. 9; FIG. 16 is a front elevational view of FIG. 9. FIG. 17 is a third top perspective view of my new design of FIG. 1; FIG. 18 is a bottom perspective view of FIG. 17; FIG. 19 is a left side elevational view of FIG. 17; FIG. 20 is a right side elevational view of FIG. 17; FIG. 21 is a top plan view of FIG. 17; FIG. 22 is a bottom plan view of FIG. 17; FIG. 23 is a rear elevational view of FIG. 17; FIG. 24 is a front elevational view of FIG. 17. FIG. 25 is a fourth top perspective view of my new design of FIG. 1; FIG. 26 is a bottom perspective view of FIG. 25; FIG. 27 is a left side elevational view of FIG. 25; FIG. 28 is a right side elevational view of FIG. 25; FIG. 29 is a top plan view of FIG. 25; FIG. 30 is a bottom plan view of FIG. 25; FIG. 31 is a rear elevational view of FIG. 25; and, FIG. 32 is a front elevational view of FIG. 25. The variety of structural elements depicted by means of broken lines in FIGS. 9-32 have been shown for environmental purposes only and form no part of the claimed design.
